US0D1055022S

(12) **United States Design Patent** (10) **Patent No.:** **US D1,055,022 S**
(45) **Date of Patent:** **** Dec. 24, 2024**

(54) **SPEAKER WITH BATTERY PACK**

(71) Applicant: **LG ELECTRONICS INC.**, Seoul (KR)

(72) Inventors: **Yongseok Kim**, Seoul (KR); **Jiwon Park**, Seoul (KR)

(73) Assignee: **LG ELECTRONICS INC.**, Seoul (KR)

(**) Term: **15 Years**

(21) Appl. No.: **35/519,361**

(22) Filed: **Nov. 10, 2023**

(80) **Hague Agreement Data**

Int. Filing Date: **Nov. 10, 2023**

Int. Reg. No.: **DM/233601**

Int. Reg. Date: **Nov. 10, 2023**

Int. Reg. Pub. Date: **Dec. 15, 2023**

(30) **Foreign Application Priority Data**

Jun. 20, 2023 (KR) 30-2023-0023550

(51) **LOC (14) Cl.** **14-01**

(52) **U.S. Cl.**

USPC **D14/204**
